Walter G. Corlett
Felted Patent

The substance referred to on these Felted Patent are making part of the same containing a description in the words of the said Walter G. Corlett himself of his improvement in carding machinery in such a form as to receive the wool from a carding machine and convert it into roving.

That which I claim as my invention or discovery in this specified machinery is the constructing of and applying it to a carding machine in such a form as to receive the wool from the machine and wind it on spools with a suitable size and twist to be spun on a jenny or otherwise. The construction of the machinery may be as follows:

The roller may be about 14 inches in diameter, made in the common form and covered with felting cards: the slugs of cards should be about 1 1/2 of an inch wide. It should be put on in slugs quite around the roller, and not less than one inch apart, so that there will be no connection of wool from one slug to another. The roller must have two motions, one rotary, the other alternate from side to side of the frame at a sufficient distance to clear the main cylinder: the motion adverse may be given by flattening the ends of the roller in a zigzag form, and placing a roller at each end on pins fast in the frame: or there may be two rollers placed one above the other and covered in the same manner, and set so that one will receive the wool where the other leaves it on the main cylinder: it may be separated from the roller in the common form with a small plate or with a set of rollers set near the card after the wool leaves the card, it is drawn through a guide by a pair of rollers from which it passes to the spindle, on which there is a stop.

that moves it as fast as it moves between the rollers: the rollers may receive their motion from the dolphine or main cylinder, and must correspond so as to receive the wool as fast as it is disengaged from the dolphine; the spindle and filer is constructed much in the form of a double spool. Spindle and filer for roping cotton: the spool and spindle must be given the motion of the spool is graduated as it falls by means of two cones, on which there is a belt that moves from one end of the cones to the other whilst the spool is falling. The spool and spindle may be driven from the main cylinder by means of a pulley on the shaft of the spool; vibrate up and down by means of a heart motion, similar to those used for cotton spinning.

"The Commissioner of Patents.
Washington, D. C."

DEPARTMENT OF THE INTERIOR,

United States Patent Office,

Washington, D. C., ... 189
SIR:

The printed ca bris of Patent No. 816,213
are exhausted.

As soon as printed a copy will be mailed you to complete your order.

By direction of the Commissioner:

Very respectfully,

Chief Clerk.
